By *R.H. Gallenbach*

Attorney

UNITED STATES PATENT OFFICE.

ARIE B. BRIGGS, OF DENVER, COLORADO.

VACUUM PRESERVER.

Application filed May 18, 1926. Serial No. 109,863.

This invention relates to a device for the preservation of perishable substances, such as food, etc., by removing the surrounding air, and has for its principal object, the provision of a gasket for a container lid which will automatically insure an air tight joint between the container and the lid.

Another object of the invention is to provide a device in which the natural suction of an automotive engine may be employed for removing the air from the container.

A further object is to provide a series of shelves in a container of this type which may be readily removed from the container to reach the contents thereof.

Other objects and advantages reside in the construction employed to obtain a highly efficient, air-tight container for this purpose and in the method used for incorporating a pump in the device. These objects and advantages will become more apparent from the following description.

In the following detailed description of the invention, reference is had to the accompanying drawings which form a part hereof. Like numerals refer to like parts in all views of the drawings and throughout the description.

In the drawings:

Fig. 1 is a side elevation through a manually operated container of the character described.

Fig. 2 is a vertical cross section through the same, taken on the line 2—2, Fig. 1.

Fig. 3 is a plan view of the container.

Fig. 4 is a horizontal cross section taken on the line 4—4, Fig. 1.

Fig. 5 illustrates a handle for removal of the shelves from the container.

Fig. 6 is a fragmentary side elevation of an automobile, illustrating the invention combined with the intake manifold of the engine thereof.

Fig. 7 is a vertical cross section, taken on the line 7—7, Fig. 6.

Fig. 8 is a detail view of the gasket construction employed in the container.

Fig. 9 is a detail view of the gasket band.

The invention comprises a container 10, provided with a surrounding gasket ring 11, spaced from the container by an annular spacer 12 which is secured to both the container and the band 11. A lid 13 having an annular rim closes the container. The periphery of the rim 14 rests upon a deep

rubber gasket 15 contained in the gasket ring 11.

Extending across the lid 13, and secured thereto, is a clamping bar 16 terminating in bifurcated extremities. Clamp bolts 17 are secured in lugs 18 on the gasket ring 11 and enter the bifurcated extremities of the bar 16, being clamped thereto by means of wing nuts 19. This arrangement removes all strain from the container since the tension of the bolts 17 is distributed between the lid and the gasket ring.

Upon the lid 13, a pump cylinder 20 is carried on legs 21 and 22, the leg 22 being hollow and acting as an intake to the pump cylinder. The leg 22 terminates in a ball valve 23 arranged to allow air to be drawn from the container 10 but preventing its return thereto. A cupped piston 24 is operated within the cylinder 20, by means of a pump handle 25.

Within the container 10, a series of angle clips 26 are secured at spaced intervals, upon which, circular shelves 27 rest. In the edge of each of the shelves 27, a series of notches 28 are formed, corresponding in spacing to the spacing of the clips 26, thus, by rotating the shelves until the notches 28 align with the clips, the shelves may be lowered or raised from the container. Either one, both, or neither of the shelves may be employed as desired. When not in use, the shelves may lie in the bottom of the container.

A central opening 29 is formed in each of the shelves to allow them to be gripped for removal. To facilitate removal, I employ a handle, as illustrated in Fig. 5, comprising a flat strip of spring metal 30 bent in a U-shape with oppositely extending feet 31. By compressing the U, it may be passed through the opening 29 and allowed to expand against the sides of the opening. The feet 31 will then lift the shelf from place.

In Fig. 6, I have illustrated an embodiment of the invention in which the vacuum in the container may be obtained from the natural suction in the intake manifold of an internal combustion engine. This form of the device is especially useful when employed as a food container for automobile touring and camping. The automobile is illustrated in outline at 32, the engine thereof at 33, and the intake manifold at 34. The container in this instance may be placed

under the rear deck of the automobile or under a seat thereof and is connected, by means of a pipe 35 controlled by a valve 36, to the intake manifold 34. Where the pipe 35 enters the container, a ball valve 38 is placed to allow air to be drawn therefrom but preventing its entry. The pump cylinder 20 may be embodied in this form to remove the air from the container when the engine is not in use. A relief valve 37 is used to break the vacuum in the container so that the lid may be removed.

In Fig. 8, I have illustrated an alternate form of the gasket ring. In this form, a gasket band 38 is employed in which the gasket ring and floor are formed as an integral part. The band 39 is soldered or welded to the container 10 and carries the gasket rubber 15 against which the lid flange 14 rests.

It is desired to call especial attention to the gasket construction employed in the device. The flexible gasket is relatively deep in the direction of pressure and relatively narrow at right angles thereto so that pressure on the lid will tend not only to force the gasket into its seat but will also expand it in all directions, thereby insuring a perfect seal. The gasket rubber is preferably made with a greater length than the circumference of its groove so that when in place, it will be under a natural compression which will expand against the walls of its seat. The novel position of the gasket removes the necessity for properly centering the lid thereon since the lid slides snugly on the exterior of the container into contact with the gasket.

The invention has been found also valuable for keeping paints, varnishes, and paint and varnish brushes from drying or hardening and is an improvement over applicant's co-pending application, Serial Number 728,399, for a device for preserving perishable substances.

While a specific form of the improvement

has been described and illustrated herein, it is desired to be understood that the same may be varied, within the scope of the appended claims, without departing from the spirit of the invention.

Having thus described the invention, what I claim and desire secured by Letters Patent is:—

1. In a vacuum preserving device comprising a container and a lid for said container, a grooved ring surrounding and secured to said container adjacent its top; a flexible gasket carried in said groove, said gasket extending above said ring; a rim formed on said lid and adapted to slide on the container wall into contact with the above extending portion of said gasket. 55

2. In a vacuum preserving device comprising a container and a lid for said container, a grooved ring surrounding and secured to said container adjacent its top; a flexible gasket carried in said groove, said gasket extending above said ring; a rim formed on said lid and adapted to slide on the container wall into contact with the above extending portion of said gasket, said gasket being relatively deep in the direction of the pressure of said rim and relatively narrow at right angles thereto. 65 70

3. In a vacuum preserving device comprising a container and a lid for said container, a grooved ring surrounding and secured to said container adjacent its top; a flexible gasket carried in said groove, said gasket extending above said ring; a rim formed on said lid and adapted to slide on the container wall into contact with the above extending portion of said gasket, said gasket having a greater normal length than 85 the circumference of said ring so that when in place it will be under compression; and means for drawing said lid toward said container. 75 80

In testimony whereof, I affix my signature.

ARIE B. BRIGGS.
